SHOE SHANK STIFFENER

Otto H. L. Thelen, Lynn, Mass.

Application December 6, 1932, Serial No. 645,901

3 Claims. (Cl. 36—76)

This invention relates to metallic stiffeners for the shanks of shoes and while not restricted thereto is particularly advantageous for use in shoes having extremely high heels and narrow shanks. In such shoes the stresses which must be taken by the shank stiffeners, particularly at about the breast of the heel, are particularly severe and the width available for the stiffeners is limited.

10 One object of this invention is to provide a stiffener of great strength for its weight and width, the strip having a reinforcing longitudinally extending rib.

15 A further object is to so form the strengthening rib that it is not liable to be flattened and the stiffener thus weakened toward its heel end where it is subjected to the most severe pounding out and to the action of heel nailing mechanism.

20 For a more complete understanding of this invention, reference may be had to the accompanying drawing in which

Figure 1 is a perspective of a stiffener embodying this invention.

25 Figures 2 and 3 are sections on corresponding-ly numbered section lines of Figure 1.

Figure 4 is a view partly in elevation and partly in longitudinal section of a shoe of the McKay or cement process type showing the 30 stiffener therein.

Figure 5 is a fragmentary plan of a McKay shoe showing the stiffener in dotted lines.

Figure 6 is a detail section on line 6—6 of Figure 5.

35 Figure 7 is a top plan of the stiffener before being molded to its longitudinal curvature.

Figure 8 is a bottom plan of the same.

Referring to the drawing, the shank stiffener shown at 1 comprises a strip of metal tapering 40 in width from the points 2 both forwardly and rearwardly. It is provided with a central stiffening rib 3 for the greater portion of its length and of substantially uniform depth, which, starting from a point substantially in lateral 45 alinement with the points 2, has its sides 4 arranged substantially parallel and close together, as is shown best in Figure 2. At about the point 5 forwardly of the points 2 the side walls 4 of the rib 3 begin to flare away from each 50 other until from about the points 6, and forwardly to substantially the break line of the stiffener at 7, these sides are so inclined from each other as to present a substantially uniform curved transverse section as shown in Figure 3. From the points 2 to the points 6 there

is a substantially flat lateral flange portion 8 on either side of the stiffening rib but from the points 6 forwardly the stiffening rib itself extends the full width of the stiffener, its edges forming continuations of the side edges of the flanges 8. Adjacent to the ends of the stiffener are suitable attaching means such as the pairs of prongs 9 and 10 by which the stiffener may be secured in position. These prongs are in substantially transversely flat end portions of 10 the stiffener, the prongs 10 being shown as positioned substantially at the break line of the shoe sole. Preferably the stiffener and the outersole are molded simultaneously to the longitudinal configuration of the shoe before being 15 applied.

The stiffener tapering forwardly from the heel end may be fitted between the tapering stitch lines 10 of a McKay shoe, as shown best in Figures 5 and 6, bearing on the inner edges of 20 the upper materials, which are secured between the innersole 11 and the outersole 12, and which form with these soles, a forwardly extending tapered pocket into which the stiffener may pass. With this arrangement pressure exerted, as by 25 the weight of the wearer on the shank stiffener tending to force it forwardly, wedges it firmly into this tapered pocket and relieves the forward end of the stiffener from the entire stress of holding the stiffener in position with reference to the sole at its forward end, this being 30 as shown and claimed in my Patent No. 1,860,437, granted May 31, 1932, for Shoes and shank stiffeners therefor. Of course a similar action takes place in the case of a cement process shoe, except that there are no lines of stitching to secure the upper materials in position 35 between the soles.

The shape of the stiffening rib at its forward portion aids in shaping the outer face of the 40 outersole but at its rear portion, particularly between the points 2 and 5, it presents a very stiff construction resistant to the flattening effects of hammer blows exerted on the shoe during the shaping of the shank portion and resistant to the blows of the heelng machine by 45 which the heel, shown at 15 in Figure 4, is secured in position. In the stiffening rib formed with flaring sides, as for example as shown in Figure 3, such blows would be quite liable to 50 flatten the rib so as to materially destroy its effectiveness in imparting stiffness to the shank stiffener. The rear end portion of the stiffener rearwardly of the points 2 is tapered in order 55 to provide more room for the driving of the

heel-securing nails as at this part of the stiffener there is no great amount of stress placed by the weight of the wearer of the shoe.

From the foregoing description of an embodiment of this invention it should be evident to those skilled in the art that various changes and modifications might be made without departing from the spirit or scope of this invention as defined by the appended claims.

10 I claim:

1. A shank stiffener comprising a metallic strip of gradually tapered width throughout the major portion of its length and having a longitudinal rib extending substantially the length 15 of said tapered portion, said rib having its sides substantially parallel and close together throughout the heel end portion and inclined from each other forwardly thereof and extended to the edges of the stiffener in the forward portion thereof, said stiffener having its widest portion toward the rear end of said heel end portion and tapering forwardly therefrom and presenting laterally flat flange portions at each side of said rib at the rear end portion only.

20 2. A shank stiffener comprising a metallic strip having a longitudinal stiffening rib ex-

tending for the major portion of its length, said rib having its sides substantially parallel and close together throughout the heel portion and inclined from each other forwardly thereof and together forming the entire width of the stiffener in the forward portion of the stiffener to the break line in a substantially uniform curve, said stiffener having flanges extending outwardly from said rib rearwardly of said forward portion.

25 3. A shank stiffener comprising a metallic strip having a longitudinal stiffening rib extending for the major portion of its length, said rib having its sides substantially parallel and close together throughout the heel portion and inclined from each other forwardly thereof and together forming the entire width of the stiffener in the forward portion of the stiffener to the break line in a substantially uniform curve, said stiffener having flanges extending outwardly from said rib rearwardly of said forward portion, the outer edges of said flanges forming continuations of the side edges of said curve in the forward portion.
